DESIGN FOR A CONDIMENTS SHAKER
OR SIMILAR ARTICLE

Joseph B. McKee, Los Angeles, Calif.

Application November 26, 1946, Serial No. 135,107

Term of patent 14 years

(CL. D44—22)

To all whom it may concern:

Be it known that I, Joseph B. McKee, a citizen of the United States, residing at Los Angeles, in the county of Los Angeles and State of California, have invented a new, original, and ornamental Design for a Condiment Shaker or Similar Article, of which the following is a specification, reference being had to the accompanying drawings, forming a part hereof, in which:

Fig. 1 is a side elevation of a condiment shaker embodying my new design;

Fig. 2 is an inverted plan view of the same;

Fig. 3 is a plan view of the same; and

Fig. 4 is a perspective view of the base.

The design includes a narrow ring interposed between the base and dome portions of the shaker, said ring being of a color shade contrasting sharply to the color shade of the base and dome portions.

I claim:

The ornamental design for a condiment shaker or similar article, as shown and described.

JOSEPH B. MCKEE.
